UNITED STATES PATENT OFFICE.

DANIEL C. JACKLING, OF REPUBLIC, WASHINGTON.

SPROCKET-WHEEL.

SPECIFICATION forming part of Letters Patent No. 708,232, dated September 2, 1902.

Application filed August 2, 1901. Serial No. 70,642. (No model.)

To all whom it may concern:

Be it known that I, DANIEL COWAN JACKLING, a citizen of the United States, residing at Republic, in the county of Ferry and State of Washington, have invented certain new and useful Improvements in Sprocket-Wheels, of which the following is a specification.

This invention relates to sprocket-wheels in which the teeth are formed independently 10 of the body portion, and particularly to the means of adjustably securing the teeth to the body portion of the wheels, so that their operative diameter or the pitch-line thereof may be increased or diminished, all of which will 15 more fully hereinafter appear.

The principal object of the invention is to provide a simple, economical, and efficient sprocket-wheel.

A further object is to provide a sprocket-wheel of such construction and arrangement that the operative diameter or pitch-line thereof may be increased or decreased the desired amount.

Further objects of the invention will appear from an inspection of the drawings and the following description and claim.

The invention consists in the features, combinations, and details of construction herein-after described and claimed.

30 In the accompanying drawings, Figure 1 is an elevation of one side of a sprocket-wheel constructed in accordance with these improvements; Fig. 2, an elevation showing the opposite side of a sprocket-wheel from that shown in Fig. 1; Fig. 3, a longitudinal sectional view taken on line 4 of Fig. 1; Fig. 4, an elevation of one of the disks forming the body portion looking at it from the interior; Fig. 5, a similar view of the other disk which 35 forms the body portion looking at it from the interior; Fig. 6, a large perspective detail view of one of the sprocket-teeth, and Fig. 7 a sectional detail taken on line 8 of Fig. 1 looking in the direction of the arrow.

45 In the art to which this invention relates it is well known that there are times when it is exceedingly desirable to increase or diminish the operative diameter of the sprocket-wheel—that is, to increase or decrease the theoretical pitch-line—to compensate for wear of either the links of the chain or the sprocket-teeth. The invention therefore is designed

principally to provide a sprocket-wheel by which such an advantage may be obtained, all of which will more fully hereinafter appear. In constructing a sprocket-wheel in accordance with these improvements I make a body portion composed of two disks *a* and *b*, the latter having a hub portion *x* extending outwardly from each side thereof. In order to provide the necessary sprocket-teeth and hold them in an adjustable manner and in engagement with the body portion of the wheel, a plurality of sprocket-teeth *c* are provided, each having a shoulder portion *d*, a supporting-bar portion *e*, and a lug portion *f* on the supporting-bar. One of the body-disks *b* is provided with a plurality of radial grooves or pockets *g*, into which the supporting-bar portion of the teeth is fitted, and the other body- 55 disk is provided with a plurality of cam-grooves *h*, adapted to receive the lug on the supporting-bar portion, so that when the parts are in operative engagement, as shown in Fig. 3, the rotation or vibratory movement 60 of the disk *a* will cause its cam to move the sprocket-teeth inwardly or outwardly toward or from the center of the wheel to diminish or increase the operative diameter thereof.

To provide means for rotatably securing the 65 disk portions that form the body of the wheel together, the body portion *b* is perforated at *t* and provided with a number of securing-bolts *i*, and the other is provided with a similar number of concentric elongated slots *k*, 70 through which the ends of the bolts on which the nuts are secured protrude. This latter rotatable disk *a* is rotatably mounted upon the hub *x* of the other disk, so that it may be rotated thereon, and is provided with a dove-tail slot *l*, into which an operating-lever *m* (shown in dotted outline) may be inserted for the purpose of moving the same. When the disk *a* has been rotated to increase or diminish the diameter of the sprocket-wheel the desired amount, the nuts on the securing-bolts 75 are securely tightened in position, thus acting to hold the parts in their desired relation.

I claim—

In a sprocket-wheel of the class described, 80 the combination of a main disk having a plurality of radial grooves in its inner side and a projecting hub, a second disk rotatably mounted upon such hub adjacent to the main

disk and provided with a plurality of tangential cam-grooves upon its inner side extending to the periphery of such disk, a sprocket-tooth slidably mounted in each of the radial grooves of the main disk and having a projecting shoulder on the inner end thereof extending into a tangential groove of the second disk, each of such teeth being provided with projecting shoulders near its outer

end for forming a chain-supporting base, and 10 bolt-and-nut mechanism for holding the disks and thereby the sprocket-teeth in position, substantially as described.

DANIEL C. JACKLING.
